Primary Examiner — Cynthia R Underwood*(74) Attorney, Agent, or Firm* — Nelson Mullins Riley & Scarborough LLP; Anthony A. Laurentano(57) **CLAIM**

The ornamental design for a bread box, as shown and described.

DESCRIPTION

FIG. 1 is a top isometric view of a bread box showing our new design;

FIG. 2 is a bottom isometric view of the new design;

FIG. 3 is a top plan view of the new design;

FIG. 4 is a bottom plan view of the new design;

FIG. 5 is a front side edge view of the new design, and rear side edge view is a mirror image; and,

FIG. 6 is a left side edge view of the new design, and the right side edge view is a mirror image.

The dashed lines indicate unclaimed portions of the claimed design and form no part of the claimed ornamental design.

1 Claim, 5 Drawing Sheets(56)
